UNITED STATES PATENT OFFICE.

BURCHARD THOENS, OF NEW YORK, N. Y.

FLUSHING VALVE.

Application filed March 6, 1923. Serial No. 623,215.

To all whom it may concern:

Be it known that I, BURCHARD THOENS, a citizen of the United States, and residing at New York city, New York County, New York State, have invented certain new and useful Improvements in Flushing Valves, of which the following is a specification.

This invention relates to automatic flushing valves, particularly of the type used to flush water closets. A great many valves of this character have been proposed in which a normally seated valve member is unseated by a hand lever and is automatically seated again after a predetermined time or after the passage of a predetermined quantity of water. These prior valves, however, are open to several serious objections; both a high water pressure and a large supply pipe are required for satisfactory operation, the valves have not been adapted to use with different heads or pressures or with different sizes of feed pipes, the mechanism for timing the seating of the valve is usually expensive, complicated and delicate, requiring frequent adjustments and repairs to prevent leaks and to insure satisfactory operation, they are frequently noisy due to water hammer, and air is apt to collect in the valve casing, necessitating periodic opening and venting.

The principal objects of my invention are to provide a valve in which the above objections have been overcome and to improve and simplify the construction in general. Other objects will be evident from the description and drawings in which:

Figure 1 is a vertical section through a valve constructed in accordance with the invention; and

Figure 2 is a top plan view of a portion thereof, cap C being removed.

Fig. 3 illustrates a variety of sizes of the disc or ring 33^b, interchangeable as herein-after described.

Referring to the drawings, the flushing valve in the embodiment of the invention illustrated, comprises a casing 10 closed at its upper end by a threaded cap C and having an inlet pipe connection 11 and an outlet pipe connection 12. The lower portion of the main body of the casing is cylindrical

and has at the bottom an outlet opening 13 and an annular or conical valve seat 13^a. This opening is controlled by a reciprocable member comprising a stem 14 and a valve member including a valve head 33^a and a ring member or disk 33^b, of larger diameter than the valve head. The valve member is provided with guides or wings 15 which insure its accurate seating, and a depending stem 16 by which it may be unseated. An arm 17 is provided for unseating the reciprocable member, this being secured to a shaft 18 mounted in the pocket 21 in the valve casing. A hand lever 22 outside the casing serves to operate the arm 17 when desired.

The valve stem 14 is secured to the valve member in any suitable manner such as by screw threads, and extending upwardly, is supported by the closing and retarding mechanism, which comprises a piston 24 threaded on the end of the valve stem and slidably fitting in a retarding chamber 25 formed in a cylindrical member 26 secured in place by a flange 27 clamped between the cap C and the casing 10. The member 26 has a number of holes 28 to allow water to pass freely from one side of the flange to the other and also has a bore 29 concentric with the piston cylinder and in which the valve stem slides.

The cylinder wall of the member 26 above the flange 27 is formed with several notches or slots 30 to provide ports for admitting water from the casing 10 to the chamber 25 when the piston is at the upper end of its travel, the location of the ports being such that they are opened to the chamber 25 only when the piston is substantially at said position. Thus the admission of water to the chamber 25 is under the control of the piston 24. The piston and valve stem may be provided with suitable packing, as shown at 31 and 32.

It is desirable that considerable time elapse between the unseating and seating of the valve member and it is also necessary to insure that sufficient pressure be maintained in the casing to cause the piston to seat the valve member when the latter is raised to open the outlet. To this end, the

lower portion 10^a of the casing in which the valve member travels is made cylindrical and is spaced from the valve member to provide a restricted passage therebetween. 5 Since the inside surface of the casing is parallel to the line of travel of the valve the effective area of this passage will remain constant throughout the limits of travel *d* of the valve member. The area of the passage is less than the area of either the inlet or the outlet openings, and thus sufficient pressure to close the valve is maintained in the casing when the outlet is opened.

10 The area of the passage can be regulated 15 in order to adapt the flushing valve to different sizes of feed pipes. For this purpose an interchangeable extension is provided on the valve member, which projects in proximity to the other member. For a given in- 20 stallation that size of extension is selected which restricts the passage to a smaller area than that of the particular feed pipe used. This extension is preferably a ring member 33^b constituting part of the valve member 25 and being secured to the valve head in any desired manner, such as by clamping between a shoulder 14^b on the valve stem and the boss 14^a of the valve head.

25 The ring member 33^b also serves as an aspirator member, a space 34 being left between the valve and aspirator member, to provide an outlet at low pressure from the retarding chamber. Water flowing through the restricted passage between the edge of 30 the aspirator member and the casing 10^a creates suction in the space 34, into which the water in the retarding chamber 25 is discharged through radial ducts 35, bore 36 in the valve stem and radial ducts 37 in the 35 valve boss. A needle valve 38 is threaded into an axial opening in the piston serving the double function of preventing the entry of any substantial quantity of water from the cap C into the bore 36 and of regulating 40 the effective area of the opening from the chamber 25 into said bore through the ducts 35. This needle valve may be adjusted by a 45 screw driver.

50 It frequently happens that air collects in the upper portion of the casing in valves of this type and causes noisy operation due to water hammer. Heretofore it has been necessary periodically to vent the air by removing a plug in the cap C. One object of 55 the present invention is to provide a suitable outlet or conduit which is opened whenever the valve is unseated to exhaust the air from the upper portion of the casing. This conduit provides communication between the 60 upper interior portion of the casing and the restricted passage in the lower portion and may be formed in any desired manner. As shown in the drawing, I prefer to employ the bore 36 and to establish communication 65 therewith by means of a small bore or duct

40 in the needle valve, leading from the upper side of the piston to the bore 36. This duct 40 is sufficiently small to prevent the flow of any appreciable quantity of water, but at the same time allows the free passage 70 of air.

75 The operation of the device is as follows: The pressure of the water in the valve casing always acts on the upper side of the piston and so normally holds the valve seated. When the lever 22 is operated, the piston and valve member rigidly connected by the valve stem, take the positions indicated by broken lines in Figure 1. Water flows 80 through the outlet opening, but since the effective area of the outlet is restricted, some considerable pressure is maintained above the valve. Communication is established between the cap C and the low pressure space 85 34 through ducts 40, 36 and 37, any air present in the cap being drawn out by the suction produced by the water flowing past the valve member. When the piston reaches its uppermost position the ports 30 are 90 opened and water flows into the piston chamber 25 filling the latter. Although some water may flow through the ducts 40 and 36 to 34, the quantity is negligible and is not sufficient to relieve the piston of the 95 pressure of the water in the casing. Therefore, when the handle is released pressure of water on the upper side of the piston begins to close the valve and as soon as the piston has descended slightly, ports 30 are closed. The valve therefore cannot close faster than 100 water can escape from the cylinder, the only outlet from the cylinder being through the ducts 35 to bore 36. Since this outlet is restricted by the needle valve 38, considerable time is required for the valve to close. 105

110 It has been found that by selecting a ring member 33^b of proper size, a given valve will operate satisfactorily with a $\frac{3}{4}$ inch supply pipe. Thus the present valve may be used in buildings which do not have large enough piping to operate the ordinary flush valve. Most of the manufacturers of prior valves will not recommend or guarantee them unless supplied by at least a $1\frac{1}{4}$ inch pipe.

115 The invention is not limited to the specific details described by way of example, but includes such modifications and changes as fall within the scope of the appended claims.

Having thus described the invention what is claimed as new and desired to be secured by Letters Patent is:

120 1. In a flushing valve, in combination, a casing having inlet and outlet openings, a reciprocable member within the casing for controlling the outlet opening, and means 125 for unseating said reciprocable member, the casing wall adjacent the path of said member being spaced from the member to form a restricted passage the effective area of which is constant irrespective of the amount 130

of movement of the member, whereby an excess of pressure is built up on one side of said reciprocable member, said reciprocable member being adapted to be automatically closed by said excess pressure.

2. In a flushing valve, in combination, a casing having inlet and outlet openings, a reciprocable member within the casing for controlling the outlet opening, and means for unseating said reciprocable member, the casing wall adjacent the path of said member being spaced from the member to form a restricted passage the effective area of which is less than the area of the outlet opening, whereby an excess of pressure is built up on one side of said reciprocable member, said reciprocable member being adapted to be automatically closed by said excess pressure.

20 3. In a flushing valve, in combination, a casing having inlet and outlet openings, a reciprocable member within the casing for controlling the outlet opening and means for unseating said reciprocable member, the casing wall adjacent the path of said member being spaced from the member to form a restricted passage the effective area of which is less than the area of the inlet opening, whereby an excess of pressure is built up on one side of said reciprocable member, said reciprocable member being adapted to be automatically closed by said excess pressure.

35 4. In a flushing valve, in combination, a casing having inlet and outlet openings, a reciprocable member, within the casing for controlling the outlet opening, and means for unseating said reciprocable member, the casing wall adjacent the path of said member being spaced from the member to form a restricted passage the effective area of which is less than the area of either the inlet or outlet opening, whereby an excess of pressure is built up on one side of said reciprocable member, said reciprocable member being adapted to be automatically closed by said excess pressure.

50 5. In a flushing valve, in combination, a casing member having inlet and outlet openings, a reciprocable member for controlling the outlet opening, means for unseating said reciprocable member, and means on one of said members cooperating with the other member to form a restricted passage to the outlet opening, whereby an excess of pressure is built up on one side of said reciprocable member, said reciprocable member being adapted to be automatically closed by said excess pressure.

60 6. In a flushing valve, in combination, a casing member having inlet and outlet openings, a reciprocable member in the casing for controlling the outlet opening, means for unseating said reciprocable member, and an extension on one of said mem-

bers, said extension cooperating with the other member to form a restricted passage to the outlet when the valve member is open, whereby an excess of pressure is built up on one side of said reciprocable member, said 70 reciprocable member being adapted to be automatically closed by said excess pressure.

7. In a flushing valve, in combination, a casing member having inlet and outlet openings, a reciprocable member in the casing for controlling the outlet opening, means for unseating said reciprocable member, and a removable extension on one of said members, said extension cooperating with the other member to form a restricted 75 passage to the outlet when the valve member is open, whereby an excess of pressure is built up on one side of said reciprocable member, said reciprocable member being adapted to be automatically closed by said 80 excess pressure.

8. In a flushing valve, in combination, a casing having inlet and outlet openings, a valve head controlling the outlet opening, means for unseating said valve head, and means adjacent the valve head extending in close proximity to the casing to form a restricted passage when the valve is open, whereby an excess of pressure is built up on one side of said valve head, said valve head being adapted to be automatically closed by 95 said excess pressure.

9. In a flushing valve, in combination, a casing member having inlet and outlet openings, a reciprocable member for controlling the outlet opening, the casing wall being spaced from the reciprocable member to form a restricted passage therebetween, means for unseating the reciprocable member, and means in the casing for seating the reciprocable member, one of said members having a conduit affording communication between the upper interior portion of the casing and said passage whereby the flow of water through said passage will produce suction in said conduit and withdraw air collected in said portion of the casing.

10. In a flushing valve, in combination, a casing member having inlet and outlet openings, a reciprocable member for controlling the outlet opening, the casing wall being spaced from the reciprocable member to form a restricted passage therebetween, means for unseating the reciprocable member, means in the casing for seating the reciprocable member, and a restricted conduit in the reciprocable member affording communication between the upper interior portion of the casing and said passage, whereby the flow of water through said passage will produce a suction in said conduit and withdraw air collected in said portion of the casing.

11. In a flushing valve, in combination, a 130 casing having an inlet opening, a cylindrical

portion and an outlet opening at one end of the cylindrical portion, a valve head in the cylindrical portion adapted to close the outlet opening, and a ring member rigidly connected to the valve head and slightly spaced therefrom, and a conduit affording communication between the upper interior portion of the casing and the space adjacent the ring member, the ring member extending in proximity to the casing whereby said space is maintained at low pressure when water flows between said ring member and casing.

12. In a flushing valve, in combination, a casing having an inlet and an outlet opening, a valve member for closing the opening having a relatively long travel, and means for unseating the valve member, the wall of the casing being spaced from the valve member to form a restricted passage of constant effective area irrespective of the extent of movement of the valve member after it has been unseated, whereby an excess of pressure is built up on one side of said valve member, said valve member being adapted to be automatically closed by said excess pressure.

13. In a flushing valve, in combination, a casing member having inlet and outlet openings, a valve head for controlling the outlet opening, means for unseating the valve head, slowly acting means for automatically seating the valve head, and a removable element carried by one of said members adjacent the outlet opening and extending in close proximity to the other member to restrict the effective area of the passage through the casing, said element being replaceable by another element of different size to adapt the valve to different sizes of feed pipes.

14. In a flushing valve, in combination, a casing having inlet and outlet openings, a valve member for controlling the outlet opening, the casing wall being spaced from the valve member to form a restricted passage therebetween, means for unseating the valve member, a piston rigidly secured to the valve member, a retarding chamber closed by the piston, the piston being subject at all times to the pressure of liquid in the casing on one side and to the pressure of liquid in the retarding chamber on the opposite side, and a restricted outlet from the retarding chamber to said passage.

15. In a flushing valve, in combination, a casing having inlet and outlet openings, a valve member for controlling the outlet opening, the casing wall being spaced from the valve member to form a restricted passage therebetween, means for unseating the valve member, a piston rigidly secured to the valve member and subject at all times to the pressure of liquid in the casing on one side, means for retarding said piston

comprising a chamber closed by the piston, the chamber having an inlet port opened to admit liquid when the valve member is unseated, and a restricted outlet from the chamber to said passage.

16. In a flushing valve, in combination, a casing having inlet and outlet openings, a valve member for controlling the outlet opening, the casing wall being spaced from the valve member to form a restricted passage, means for unseating the valve member, a piston rigidly secured to the valve member and subject at all times to the pressure of liquid in the casing on one side, means for retarding said piston comprising a chamber closed by the piston, the chamber having an inlet port opened by the piston to admit liquid to the chamber when the valve member is unseated, and a restricted outlet passage in the valve member affording communication between the chamber and said first passage.

17. In a flushing valve, in combination, a casing having inlet and outlet openings, a valve member for controlling the outlet opening, the casing wall being spaced from the valve member to form a restricted passage therebetween, means for unseating the valve member, a piston rigidly secured to the valve member, a retarding chamber closed by the piston, the piston being subject at all times to the pressure of liquid in the casing on one side and to the pressure of liquid in the retarding chamber on the opposite side, a restricted outlet from the retarding chamber to said passage, and means for exhausting air from the upper interior portion of the casing when the valve is unseated.

18. In a flushing valve, in combination, a casing having inlet and outlet openings, a valve member for controlling the outlet opening, the casing wall being spaced from the valve member to form a restricted passage therebetween, means for unseating the valve member, a piston rigidly secured to the valve member, a retarding chamber closed by the piston, the piston being subject at all times to the pressure of liquid in the casing on one side and to the pressure of liquid in the retarding chamber on the opposite side, a restricted outlet from the retarding chamber to said passage, and a conduit affording communication between the upper side of the piston and said outlet.

19. In a flushing valve, in combination, a casing having inlet and outlet openings, a valve head for controlling the outlet opening, the casing wall being spaced from the valve member to form a restricted passage therebetween, means for unseating the valve head, an aspirator member secured to the valve head and adjacent thereto, a hollow stem secured to the valve head and communicating with the space between the valve

head and aspirator member, a cylindrical member having a retarding chamber therein, a piston closing the chamber, the valve stem passing through the chamber and

5 being secured to the piston, ports in the chamber uncovered by the piston when the valve head is unseated, a restricted outlet

from the chamber into the valve stem, and a passage affording communication between the upper side of the piston and the valve 10 stem.

In testimony whereof I hereunto affix my signature.

BURCHARD THOENS.
